CLAIM

The ornamental design for an intake bezel, as shown and
described.

DESCRIPTION

FIG. 1 is a first perspective view of an intake bezel according
to a first exemplary embodiment of our new design for use
on a first side of a vehicle;

FIG. 2 is a second perspective view of the intake bezel
shown in FIG. 1;

FIG. 3 is a front elevational view of the intake bezel shown
in FIG. 1;

FIG. 4 is a top view of the intake bezel shown in FIG. 1;
FIG. 5 is a bottom view of the intake bezel shown in FIG.
1;

FIG. 6 is a left side view of the intake bezel shown in FIG.
1;

FIG. 7 is a right side view of the intake bezel shown in FIG.
1;

FIG. 8 is a first perspective view of an intake bezel according
to a second exemplary embodiment of our new design for
use on a second side of a vehicle;

FIG. 9 is a second perspective view of the intake bezel shown
in FIG. 8;

FIG. 10 is a front elevational view of the intake bezel shown
in FIG. 8;

FIG. 11 is a top view of the intake bezel shown in FIG. 8;
FIG. 12 is a bottom view of the intake bezel shown in FIG.
8;

FIG. 13 is a left side view of the intake bezel shown in FIG.
8; and,

FIG. 14 is a right side view of the intake bezel shown in FIG.
8.

The rear of the intake bezel is unornamented.

The broken lines shown in the figures represent portions of
the intake bezel that form no part of the claimed design.
While the accompanying drawings include broken lines that
form no part of the claimed design, the broken lines provide
written description of prospective embodiments that are
claimed when one or more of the broken lines are amended
to solid lines. Similarly, while the solid lines in the drawings
form part of the claimed design, the solid lines provide
written description of prospective embodiments that are not
claimed when one or more of the solid lines are amended to
broken lines.
